Primary Examiner — Leanne Was-Englehart*(74) Attorney, Agent, or Firm* — Calderon Safran Cole PC(57) **CLAIM**

The ornamental design for a taillight for a vehicle, as shown and described.

DESCRIPTION

FIG. 1 is a front view of a taillight for a vehicle showing my new design;

FIG. 2 is a left perspective view thereof;

FIG. 3 is a left side view thereof; and,

FIG. 4 is a top view thereof.

The broken line(s) which define the bounds of the claimed design form no part thereof. Outside the broken line boundary, the de-emphasized and halftone showing of a motor vehicle illustrates environment and forms no part of the claimed design.
